UNITED STATES PATENT OFFICE.

CHARLES L. GOEHRING, OF ALLEGHENY, PENNSYLVANIA.

ROTARY CUTTER-HEAD.

SPECIFICATION forming part of Letters Patent No. 445,335, dated January 27, 1891.

Application filed April 19, 1890. Serial No. 348,724. (No model.)

To all whom it may concern:

Be it known that I, CHARLES L. GOEHRING, of Allegheny, in the county of Allegheny and State of Pennsylvania, have invented certain new and useful Improvements in Rotary Cutter-Heads for Molding and Planing Machines; and I do hereby declare the following to be a full, clear, and exact description of the same, reference being had to the accompanying drawings, forming a part of this specification, and to the letters of reference marked thereon.

This invention relates to a new and improved cutter-head designed more especially for use in connection with molding-machine cutters, although applicable to other similar uses; and it consists in the novel and improved construction, combination, and arrangements of parts, as hereinafter fully described, and pointed out in the claims.

In the drawings, Figure 1 is a side elevation, and Fig. 2 a front or edge elevation, of the improved cutter-head. Fig. 3 is a longitudinal section on the line $x-x$, Fig. 1; and Fig. 4 is a similar section on line $y-y$, Fig. 2. Fig. 5 is a transverse sectional view on line $z-z$, Fig. 1. Figs. 6 and 7 are side and front views, respectively, of the sections of the head detached and separated. Fig. 8 is a transverse sectional view of the head with cutters in position.

Similar letters of reference in the several figures indicate the same parts.

The improved cutter-head is formed in two sections A B, movable longitudinally the one upon the other and provided with a central orifice for the accommodation of the shaft or spindle to which the cutter-head is to be applied. The principal section A is formed or provided with a tubular extension a , fitted to receive the other section B, the latter properly guided, as by pins b , to move longitudinally upon tubular extension a , while a nut C or equivalent clamping or adjusting devices is applied to the outer end of the tubular extension a and operates upon the section B to force and hold the two together. The opposite sides of the sections have arc-shaped faces $a' b'$, and one or both sections (preferably both) are reduced on lines parallel with the curved faces $a' b'$, the shoulders $a^2 b^2$ thus formed being undercut or inclined substantially as shown, thus producing, when the sec-

tions are associated together, an undercut or dovetail groove.

The knives or bits D used with the cutter-head are arc-shaped and furnished on their inner faces with dovetails or ribs d , suited to be engaged and clamped within the groove formed between shoulders $a^2 b^2$.

When a cutter or bit is to be inserted, the nut or fastening device is retracted and the rib on the arc-shaped bit is entered between the shoulders $a^2 b^2$ on the two sections A B, and the bit is then slid to place, with its cutting-edge projecting beyond the circumference of the head. The nut is then tightened up, thereby not only clamping the rib d between the shoulders $a^2 b^2$, but at the same time pressing the bit firmly against the face of the head, said face being cut to the arc of the inner face of the bit and extending to or beyond the sides of the bit, thus forming an extended bearing-surface against which the bit rests and is clamped and held.

By mounting the section B to slide longitudinally upon the tubular extension of section A two important advantages are gained. In the first place, the cutter-head and cutters can be adjusted and fixed before being applied to the shaft or spindle and can be adjusted as a whole upon the spindle, and, in the second place, a long and large bearing or guide is formed for the movable section B upon the section A, one which will obviate tilting and cramping when moving the section B to release or clamp the bits and will insure the proper support for the latter when applied. The interlocking projections or pins b serve, principally, to guide the sections and prevent the rotation of the one upon or with reference to the other, and other equivalent devices may be used or substituted for this purpose.

As the bits become worn or are ground off they are shifted upon their seats to bring the cutting-edge at the desired distance from the center of the head, and the same cutters or bits can be employed upon heads of different dimensions and for cutting in larger or smaller circles by forming the bearing-faces of the heads with the same curvature as the inner faces of the bits.

The cutter-head shown is of relatively small dimensions, and it is for the smaller sizes

that the present invention is most advantageously employed, dispensing with the clamping-screws heretofore used for holding the bits in place, and at the same time providing ample support and bearing for retaining the bits securely in place and preventing springing or displacement when in action.

Having thus described my invention, what I claim as new is—

- 10 1. The improved cutter-head herein described, comprising two sections movable the one longitudinally of the other and guided upon a tubular extension thereof, each section being furnished with undercut shoulders and exterior bearing-faces for the reception of the bits, substantially as described.
- 15 2. The combination, with the head or section A, provided with exterior curved faces and an undercut shoulder, of the section B, guided to move toward section A and provided with exterior curved faces and a corresponding undercut shoulder, and means for clamping the two sections together and upon the rib formed on the back of a curved bit, substantially as described.
- 20 3. The hereinbefore-described improved cutter-head, comprising the section A, formed with tubular extension, exterior bearing-faces, and an undercut shoulder, the section B, fitted to the tubular extension of section A and provided with exterior bearing-surfaces and undercut shoulders, and bits provided with a dovetailed rib extending longitudinally there-

of and adapted to be received between the undercut shoulders on sections A B and having the faces on opposite sides of said rib fitted to and resting in contact with the exterior bearing-faces of the sections A B, substantially as described.

4. The hereinbefore-described improved cutter-head, composed, essentially, of two sections A B, provided with exterior curved bearing-faces conforming substantially to the curved inner face of the bit, with intermediate undercut shoulders forming a dovetail groove, one of said sections being guided to move longitudinally upon the other and provided with interlocking portions to prevent rotation, substantially as described.

5. In a cutter-head such as described, the combination of the section A, having arc-shaped surfaces or sides a' and undercut shoulders a^2 and provided with a tubular extension a , the section B, fitted to slide upon tubular extension a and provided with arc-shaped surfaces b' and undercut shoulders b^2 , the pins engaging the sections to prevent rotation, the nut applied to the tubular extension and engaging movable section B, and the curved bit provided with narrower dovetailed ribs fitted and clamped between shoulders a^2 b^2 , substantially as described.

CHARLES L. GOEHRING.
